United States Patent

Des. 234,298
Patented Feb. 11, 1975

234,298

SEPTIC TANK

William M. Bower, Suffield, Conn., assignor to Bangor Punta Operations, Inc., Greenwich, Conn.

Original design application May 17, 1973, Ser. No. 361,353. Divided and this application July 19, 1974, Ser. No. 489,860

Term of patent 14 years

Int. Cl. D23—01
U.S. Cl. D23—2

FIG. 1

FIG. 2

FIG. 1 is a side elevation of a septic tank showing my new design, the opposite side being a mirror image of the side shown.

FIG. 2 is a top plan view thereof.

This is a division of design application, Ser. No. 361,353, filed May 17, 1973.

I claim:

The ornamental design for a septic tank, substantially as shown and described.
